PAPER CUTTER

George J. Wolnez, Sacramento, Calif., assignor to Aero-jet-General Corporation, El Monte, Calif., a corporation of Ohio

Filed Dec. 30, 1964, Ser. No. 83,223

Term of patent 14 years

(Cl. D22—3)

The figure on the drawing is a perspective view of a paper cutter, showing my new design. The essential features of the design reside in the portions shown in solid lines on the drawing. The broken-line showing of parts of a supporting table are merely for purposes of illustration only. The diagonal shading lines indicate a transparent condition.

I claim:

The ornamental design for a paper cutter, as shown and described.
